UNITED STATES PATENT OFFICE.

MILTON TAYLOR HANCOCK, OF SHREVEPORT, LOUISIANA.

ROTARY-DISK PLOW.

SPECIFICATION forming part of Letters Patent No. 643,499, dated February 13, 1900.

Application filed December 5, 1899. Serial No. 739,284. (No model.)

To all whom it may concern:

Be it known that I, MILTON TAYLOR HANCOCK, a citizen of the United States of America, and a resident of Shreveport, in the parish of Caddo and State of Louisiana, have made a certain new and useful Improvement in Rotary-Disk Plows; and I do hereby declare the following to be a full, clear, and exact description of the invention, such as will enable others skilled in the art to which it appertains to make and use the same, reference being had to the accompanying drawings, which form part of this specification.

This invention relates to rotary-disk plows in which the plowing is done by a disk which is rotatably mounted upon a suitable frame.

The object of the invention is to provide an improved beam or frame and frame adjustment, to improve the disk and its mounting in such a manner that the said disk will not be torn from its fastenings or become loosened, and to provide an improved scraper and adjustment therefor which insures the clearing of the face of the disk and facilitates the turning of the dirt in the furrow, the details of all of which will be hereinafter fully specified.

In the accompanying drawings, Figure 1 is a plan view, and Fig. 2 is a side elevation, of the plow complete. Fig. 3 is a sectional view of the disk and the mounting therefor. Fig. 4 is a side elevation of the same parts, showing the scraper and the adjusting device. Fig. 5 is a face view of the disk, showing the peculiar form of the scraper. Figs. 6 and 7 are enlarged detail sectional views showing the pivotal connections between the beam-sections.

In the figures like reference characters are uniformly employed in the designation of corresponding elements of construction.

As best shown in Fig. 1, the beam consists of three sections marked 1, 2, and 3, respectively, which are pivotally secured together and provided with such stops as would be deemed desirable for limiting a lateral movement relative one to each other. As shown in Figs. 1 and 7, the forward beam-section 3 and the second or intermediate beam-section 2 are pivotally connected by means of a vertically-arranged pin 3^a, and, as shown in said Fig. 1 and also Figs. 2 and 6, the beam-sections 1 and 2 are pivotally connected by means of a pin 2^a in the particular instance in the drawings, said pin being formed by a bent-over portion of the beam-section 1. The front section 3 is made of a flat spring. It is to this section 3 that the tongue is secured by means of a simple clevis 4, which, however, need not be itself vertically-adjustable, inasmuch as the resilience of the portion of the beam 3 provides for any desired adjustment thereof. Under the section 3 of the beam there is mounted a vertically-adjustable gage-wheel 5, made adjustable by means of a sliding block 6, Fig. 2, and suitable connections with the lever 7, whereby said block may be moved along a vertical guide 8, as best shown in Fig. 1. To the forward end of the section 2 of the beam is secured a bent axle 9, which is partially rotatable by means of the lever 10, secured thereto, and carries on its offset end a wheel 11. The portion 1 of the beam consists, preferably, of a bar pivotally secured to the back end of the section 2 of the beam and having its end turned outwardly and downwardly, carrying a wheel 12, which forms the third bearing-point for the plow. To the back end of the section 2 of the beam is secured a suitable seat 13. There being a wheel upon each section of the beam, the various strains are divided between said sections as far as the carrying of the weight is concerned. The central section 2 of the beam is bent laterally at about its middle portion, its front portion lying substantially parallel to the line of draft, while the back portion lies at an angle thereto in a substantially horizontal plane. Secured to and projecting downwardly from this angular portion of said beam is a hanger 14, which has upon its lower end a hanger perforated at an angle downwardly. This lug may obviously be of many forms; but it should be capable of being secured to the said section 2 of the beam with the utmost rigidity. The lug at the lower end is perforated axially and the disk 15 concaved upon its face and having an annular depression therein and being provided with a stem 16 is mounted by said stem therein, so as to rotate freely. The said disk 15 and stem 16 are perforated concentrically, and in the face of the disk, concentric with the said perforation, is a conical opening.

tions 1 and 2 are pivotally connected by means of a pin 2^a in the particular instance in the drawings, said pin being formed by a bent-over portion of the beam-section 1. The front section 3 is made of a flat spring. It is to this section 3 that the tongue is secured by means of a simple clevis 4, which, however, need not be itself vertically-adjustable, inasmuch as the resilience of the portion of the beam 3 provides for any desired adjustment thereof. Under the section 3 of the beam there is mounted a vertically-adjustable gage-wheel 5, made adjustable by means of a sliding block 6, Fig. 2, and suitable connections with the lever 7, whereby said block may be moved along a vertical guide 8, as best shown in Fig. 1. To the forward end of the section 2 of the beam is secured a bent axle 9, which is partially rotatable by means of the lever 10, secured thereto, and carries on its offset end a wheel 11. The portion 1 of the beam consists, preferably, of a bar pivotally secured to the back end of the section 2 of the beam and having its end turned outwardly and downwardly, carrying a wheel 12, which forms the third bearing-point for the plow. To the back end of the section 2 of the beam is secured a suitable seat 13. There being a wheel upon each section of the beam, the various strains are divided between said sections as far as the carrying of the weight is concerned. The central section 2 of the beam is bent laterally at about its middle portion, its front portion lying substantially parallel to the line of draft, while the back portion lies at an angle thereto in a substantially horizontal plane. Secured to and projecting downwardly from this angular portion of said beam is a hanger 14, which has upon its lower end a hanger perforated at an angle downwardly. This lug may obviously be of many forms; but it should be capable of being secured to the said section 2 of the beam with the utmost rigidity. The lug at the lower end is perforated axially and the disk 15 concaved upon its face and having an annular depression therein and being provided with a stem 16 is mounted by said stem therein, so as to rotate freely. The said disk 15 and stem 16 are perforated concentrically, and in the face of the disk, concentric with the said perforation, is a conical opening.

As best shown in Fig. 1, the beam consists of three sections marked 1, 2, and 3, respectively, which are pivotally secured together and provided with such stops as would be deemed desirable for limiting a lateral movement relative one to each other. As shown in Figs. 1 and 7, the forward beam-section 3 and the second or intermediate beam-section 2 are pivotally connected by means of a vertically-arranged pin 3^a, and, as shown in said Fig. 1 and also Figs. 2 and 6, the beam-sections 1 and 2 are pivotally connected by means of a pin 2^a in the particular instance in the drawings, said pin being formed by a bent-over portion of the beam-section 1. The front section 3 is made of a flat spring. It is to this section 3 that the tongue is secured by means of a simple clevis 4, which, however, need not be itself vertically-adjustable, inasmuch as the resilience of the portion of the beam 3 provides for any desired adjustment thereof. Under the section 3 of the beam there is mounted a vertically-adjustable gage-wheel 5, made adjustable by means of a sliding block 6, Fig. 2, and suitable connections with the lever 7, whereby said block may be moved along a vertical guide 8, as best shown in Fig. 1. To the forward end of the section 2 of the beam is secured a bent axle 9, which is partially rotatable by means of the lever 10, secured thereto, and carries on its offset end a wheel 11. The portion 1 of the beam consists, preferably, of a bar pivotally secured to the back end of the section 2 of the beam and having its end turned outwardly and downwardly, carrying a wheel 12, which forms the third bearing-point for the plow. To the back end of the section 2 of the beam is secured a suitable seat 13. There being a wheel upon each section of the beam, the various strains are divided between said sections as far as the carrying of the weight is concerned. The central section 2 of the beam is bent laterally at about its middle portion, its front portion lying substantially parallel to the line of draft, while the back portion lies at an angle thereto in a substantially horizontal plane. Secured to and projecting downwardly from this angular portion of said beam is a hanger 14, which has upon its lower end a hanger perforated at an angle downwardly. This lug may obviously be of many forms; but it should be capable of being secured to the said section 2 of the beam with the utmost rigidity. The lug at the lower end is perforated axially and the disk 15 concaved upon its face and having an annular depression therein and being provided with a stem 16 is mounted by said stem therein, so as to rotate freely. The said disk 15 and stem 16 are perforated concentrically, and in the face of the disk, concentric with the said perforation, is a conical opening.

17 is the plow-disk, which is concaved, as usual; but instead of having the usual small hole in its center, made by removing a certain portion of the metal at that point, it has 5 the metal pressed into funnel shape, whereby a conical hollow lug is formed upon the back side of the disk 17 and the disk so strengthened and stiffened at that point that all danger of buckling or tearing under ordinary 10 strains is done away with.

18 is a bolt which is adapted to pass through the longitudinal perforation of the backing-disk 15 and its stem 16 and is provided with a head conical in form to fit the conical interior 15 of the lug on the disk 17, so that when said bolt is tightened into place the said conical head is drawn firmly into the aforesaid conical lug, drawing it in turn into the conical recess in the front of the disk 15, expanding 20 it to fit therein, and firmly drawing the disk 17 into contact with the face of the disk 15, and the outer side of the said conical lug on the disk 17 into firm, reliable, frictional contact with the conical recess aforesaid.

25 19 is a washer which is adapted to be drawn by the nut 20 upon the bolt 18 into contact with the end of the stem 16, but slightly short of contact with the end of the hub on the hanger 14, whereby it is plain that the bolt 30 18 will be drawn to operation, as aforesaid, without causing the binding of the stem 16 in its bearing.

Secured to the hanger 14 is an arm 21, which is extended in such direction and should 35 be of such shape and size as will carry the parts to be attached thereto, having, however, its upper end bent into approximately a horizontal position and dentated on its upper surface. A slot is made therein opening down-40 wardly through said dentated surface, and upon this said surface rests a block 22, perforated to receive the bolt 23 and dentated upon its lower surface correlative with the upper surface of the bar 21. The bolt 23 45 passes downwardly through the said block 22 and the slot in the arm of the bracket 21 and through a foot 24 on the upper end of a standard 25. On the lower end of this standard, secured thereto in any suitable manner, but 50 preferably by rivets or countersunk bolts, is the scraper 26. This scraper is formed, as best shown in Figs. 4 and 5, in the shape of a section of a hollow cylinder of edge contour approximately as shown, by means of which 55 the scraper-point 27 is brought to substantially the center of the bolt 18, and the said cylindrical section is made to fit or correspond to the concavity in the disk 17. The upper outer corner of this scraper extends slightly 60 beyond the edge of the disk in order that the dirt cleared and turned by the said scraper shall in no wise again come in contact with the plow-disk. It will be seen, especially upon reference to Fig. 5, that this form of 65 scraper will always conform to the concave face of the disk and be brought into contact with the said face and will wear in such a

manner as will continue to fit; further, that the scraper-point 27 at the center of the disk affords extremely little resistance to the passage of the dirt taken from the furrow from the face of the disk across said scraper, and that said scraper, partaking somewhat of the nature of the moldboards of a turn-plow, will not only perform this function of scraping, 75 but will also do the work of such moldboard. The scraper will at all times be braced under excessive strain against any resilient movement by contacting with the concaved face of the disk, while it may be adjusted to and 80 from such contact to any necessary extent by means of the bolt 23 and the block 22, engaging, as before stated, the dentated surface upon the bracket 21.

It will be understood that as the forward 85 beam-section 3 is made of spring-steel or other suitable resilient material it will be free to move up and down, so as not to require any adjustment for a high or low hitch, and this also prevents throwing the doubletree up and 90 down when the wheels run over uneven surfaces. The plow is made much more effective by having a wheel separately mounted on each beam-section, as the various strains are thereby equalized or divided between said sections. 95

The funnel-shaped opening in the center of the plow-disk not only serves as a recess for the head of the bolt, but strengthens that part of the disk and obviates any liability of its being torn out or broken. By curving 100 the lower edge of the scraper 26 in such manner as to cause it to fit the concavity of the plow-disk it will not only more effectively clean said disk, but at the same time will carry off and turn over the soil. The provisions made for adjustment of this scraper are of such a character that the scraper will 105 be braced at all times against any excessive strain, while at the same time the scraper may be adjusted to and from the concaved 110 face of the plow-disk to any extent desired.

Having thus described my invention, what I claim as new, and desire to secure by Letters Patent of the United States, is—

1. In a rotary-disk plow, a frame consisting of three sections pivotally connected by their correlative ends so as to have movement in a horizontal plane, a wheel mounted on each section and a plowing-disk mounted on the intermediate section. 115

2. In a rotary-disk plow, a beam consisting of three pivotally-connected sections, a wheel mounted on the front section near its back end, a wheel mounted on the intermediate section near its front end in apposition to the 125 first-named wheel, a wheel mounted on the free end of the back section, and a plowing-disk mounted on the intermediate section.

3. In a rotary-disk plow, a frame consisting of three sections, the front section being of 130 resilient material, and provided at its front end with means for attaching the draft-animals, said sections being pivotally connected by the correlative ends so as to have move-

ment in a horizontal plane, a wheel mounted on each section and a plowing-disk mounted on the intermediate section.

4. In a rotary-disk plow, a plow-disk having a perforated conical projection upon its back side at its center and means for mounting the said plowing-disk consisting of a backing-disk axially perforated and adapted to be mounted rotatably and provided with a conical recess in its center adapted to receive the aforesaid conical projection upon the plowing-disk and a bolt adapted to pass through said disks and clamp them together.

5. In a rotary-disk plow, a plowing-disk having a hollow lug projecting from its back side and correlatively conical as to its interior and exterior sides, and means for mounting the said plowing-disk consisting of a backing-disk concave on its face, axially perforated, and provided with a conical recess in its center adapted to fit the said conical lug and a bolt having a conical head and adapted to pass through said plowing and backing disks and clamp them together.

6. In a rotary-disk plow, a plowing-disk having the metal at its center pressed backwardly to form a hollow lug perforated at its apex and correlatively conical as to its interior and exterior sides, and means for mounting the said plowing-disk consisting of a backing-disk concave on its face, axially perforated, provided with a conical recess in its center adapted to fit the said conical lug and a bolt having a conical head and adapted to pass through said plowing and backing disks and clamp them together.

7. As a new article of manufacture a disk for rotary-disk plows, formed from a single sheet of metal cut in circular form, bent conically and having the metal in its center pressed beyond its convex side so as to form a hollow cone perforated at its apex.

8. In a rotary-disk plow, a plowing-disk and a scraper supported in operative relation to the concaved face of said disk and consisting of a plate of metal bent in the approximate form of a segment of a cylinder, its lower edge being curved to conform to the concave disk.

9. In a rotary-disk plow, a plowing-disk and

a scraper supported in operative relation to the concaved face of said disk and consisting of a plate of metal bent in the approximate form of a segment of a cylinder, its lower edge being curved to conform to the concave disk, and its upper edge being curved at the inner corner said curved edges converging in a point opposite the center of the disk.

10. In a rotary-disk plow, a rotatably-mounted plow-disk, a scraper mounted in operative relation to the concaved face of said disk and having its lower edge curved to conform thereto, an arm secured to said scraper and provided with a foot on its upper end, a bracket also provided with a foot on its upper end, said last-named foot being dentated on its upper face and slotted, a perforated block correlatively dentated on its lower side, and a bolt adapted to pass through said block and feet and clamp the same rigidly together.

11. In a rotary-disk plow, a rotatably-mounted plowing-disk of concave form and provided at the center with an axially-perforated cone projecting beyond the convex side of said disk, means for mounting the plowing-disk through said hollow cone, and a scraper consisting of a plate of metal bent in the approximate form of a segment of a cylinder and having its lower edge curved to conform to the concaved face of said plow-disk.

12. In a rotary-disk plow, a rotatably-mounted plowing-disk having a concave face, a scraper consisting of a plate of metal bent to the approximate form of a segment of a cylinder and having its lower edge curved to conform to the concaved face of the plowing-disk and the upper edge curved at its inner corner, said curved edges of the scraper being converged in a point opposite the center of the plowing-disk, and means for mounting said plowing-disk and scraper in operative relation.

In testimony whereof I hereunto affix my signature in presence of two witnesses.
